UNITED STATES PATENT OFFICE.

JOHN F. ELLIS, OF WASHINGTON, DISTRICT OF COLUMBIA, ASSIGNOR OF ONE-HALF TO
MARIE J. ELLIS, OF WASHINGTON, DISTRICT OF COLUMBIA.

RAZOR-STROP-CONNECTING DEVICE.

1,414,267.

Specification of Letters Patent. Patented Apr. 25, 1922.

Application filed January 28, 1921. Serial No. 440,680.

To all whom it may concern:

Be it known that I, JOHN F. ELLIS, a citizen of the United States, residing at Washington, in the District of Columbia, have invented new and useful Improvements in Razor-Strop-Connecting Devices, of which the following is a specification.

The object of my present invention is the provision of a simple, inexpensive and easily manipulated device through the medium of which a razor strop may be connected to a barber's chair or any other chair or object or projection, and this expeditiously and without the necessity of tying the razor and in such manner that the razor strop may be manipulated and handled to the best advantage.

I would also have it understood that it is within the purview of my invention to equip my novel connecting device in such manner that the same may be employed to connect one or a plurality of razor strops to a common object.

To the attainment of the foregoing, the invention consists in the improvement as hereinafter described and definitely claimed.

In the accompanying drawings, forming part hereof:—

Figure 1 is a perspective illustrating my novel connecting device as properly arranged relatively to a razor strop and the arm of a barber's chair.

Figure 2 is a plan view of my novel connecting device per se.

Similar numerals of reference designate corresponding parts in both views of the drawings.

The barber's chair 1 is not of my invention and need not therefore be referred to in detail.

I would also have it understood that the razor strop 2 may be of any type compatible with the use of my novel connecting device, the strop illustrated being shown as equipped at its heel end with a swivel attachment 3 the outer member of which is in the form of an eye.

My novel connecting device comprises a flexible strap 4 which is preferably of leather, though it may be of any other material compatible with its purpose, and a

hook 5 on the said strap adjacent to one end thereof; the said hook being preferably, though not necessarily, a safety hook. The strap 4 is provided adjacent to its end remote from the end portion bearing the hook or other coupling 5 with an opening 6, the said opening being elongated as illustrated in the direction of the width of the strap. I would also have it understood that the portion 7 of the strap adjacent to the hook or coupler 5 is of a relative width—i. e., comparatively narrow to enable it to pass through the aperture 6 without distortion of said portion 7. The portion 8 of the strap between the portion 7 and the portion in which the aperture 6 is formed is of relatively increased width—i. e., comparatively wide, and is provided with a slot or lengthwise elongated opening 9 so as to afford two strap portions 10 adapted to neatly accommodate themselves to a chair arm or to any other object to which the connecting device is applied.

In the practical use of my novel connecting device, the portion 8 of the device is looped about an object such for instance as the chair arm shown, and the portion 7 is passed through the aperture 6, and is drawn upon so as to render the loop taut on the arm of the chair or on any other object to which the device is applied, after which the strop 2 is coupled to the connecting device.

Manifestly the operation described may be quickly and easily carried out without the delay entailed by tying or the like, and without the liability of marring the chair arm or other object to which the connecting device is applied. It will also be appreciated that by reason of the flexible character of my novel connecting device the same is adapted to lend and accommodate itself to the position in which the strop is held and to the various movements of the strop incident to a razor stropping operation.

It will further be apparent from the foregoing that my novel connecting device as shown in Figure 2 is susceptible of being cheaply manufactured so that it is feasible to sell it for a price so low that it will be placed within the reach of everyone.

Having described my invention, what I

claim and desire to secure by Letters-Patent, is:—

As a new article of manufacture, a connecting device for razor strops comprising a strap of flexible material and a coupler carried on one end portion of the strap to fasten the same to a razor strop; the said strap being provided with a relatively wide

end and major portion and a transverse aperture therein adjacent to one end of the strap, and being further provided in said wide portion with a lengthwise elongated opening whereby spaced longitudinal strap portions are afforded.

In testimony whereof I affix my signature. 15

JOHN F. ELLIS.
